HEATING, DRYING, AND STERILIZING
CABINET

Walter Lawrence Gill, Redlands, Calif.

Application October 14, 1936, Serial No. 105,596

2 Claims. (Cl. 219—35)

This invention relates to heating, drying and sterilizing cabinets for towels and the like, adapted for use in hospitals, barber shops, beauty parlors and the like, as well as in private homes.

5 The cabinet of the present invention has the same general purpose as that illustrated in my co-pending application, Serial No. 726,374, filed May 18, 1934, in the names of Volney C. Kincaid, and myself, Patent No. 2,060,065, November 10,

10 1936.

It is a primary object of the present invention to provide a cabinet having a plurality of shelves and means for individually heating said shelves, with either a low, medium or high degree of heat, and to accomplish this result through the medium of a structure which may be economically and cheaply manufactured, will be suitably insulated against the loss of heat, will present a pleasing appearance and constitute an attractive article of furniture, and which may, if desired, in addition provide means for circulating either warm or cool air in the bathroom, nursery, or other room in which the cabinet may be located.

25 In the accompanying drawings, which illustrate one embodiment of the invention, chosen merely for purposes of explanation:

Figure 1 is a front elevation of a cabinet constructed in accordance with the invention;

30 Fig. 2 is a plan view thereof;

Fig. 3 is a side elevation thereof;

Fig. 4 is a transverse vertical sectional view;

Fig. 5 is a front elevation with the door removed;

35 Fig. 6 is a diagrammatic view illustrating medium and low heating units arranged in a continuous series to traverse the under sides of the several shelves, as hereafter set forth, and

Fig. 7 is a fragmentary sectional view illustrating a modified form embodying a fan for aiding in the circulation of air.

Like numerals designate corresponding parts throughout the several figures of the drawings.

Referring to the drawings, 5 designates the 45 outer shell of the cabinet, the forward side of which is provided with a doorway. The material of the outer shell 5 is turned inwardly, as indicated at 6. An inner shell 7 is attached at its forward edge to the inturned portions 6

50 by suitable fastening devices 8. A door 9, provided with an ornamental handle 10, such for example as those commonly employed in refrigerators and the like, closes the forward side of the cabinet, being hinged as indicated at 11.

55 It will be observed that the construction de-

scribed provides a double-walled cabinet, with a space 12 between the inner and outer shells. This space may be utilized to effect suitable heat insulation of the cabinet, by lining the interior of the outer shell with a sheet of heat-reflectant, insulating material 13 such as rock wool, or the like. The door may likewise be suitably insulated, in a manner common to refrigerator construction.

It will readily be understood that the exterior 10 of the inner shell may carry a sheet of heat-reflecting insulation, such as aluminum foil or the like, either in lieu of that carried by the outer shell or in addition thereto.

The inner shell (which defines the internal dimensions of the cabinet) is laterally spanned, 15 by a plurality of shelves 14, and these shelves are preferably provided with down-turned edges 15. The shelves are of such width as to be slightly spaced from the rear wall of the cabinet, as indicated at X, and to be slightly spaced from the inner face of the door when the door is closed, as indicated at Z. Thus, air may circulate within the cabinet.

Vents for the passage of air are provided by 25 a row of openings 16, beneath the lowermost shelf and above the bottom of the cabinet, and by another row of openings 17, between the uppermost shelf and the top of the cabinet, these openings passing through the walls of both the 30 inner and outer shells and the sheet of insulating material 13. If desired, tubes or thimbles 18 may be provided to span the space between the shells and to provide passageways for the exterior air. The natural tendency of the heated 35 air to rise would cause the entry of air through tubes 16 and the discharge of such air through openings 17.

The several shelves carry sheet metal wiring ducts 19 upon their under sides, and the bottom 40 of the cabinet likewise carries a sheet metal wiring duct 20 upon its under side. A switch plate 21, carrying switches 22 and 23, is secured at the side of the cabinet. The wiring, indicated in Fig. 6, consists of the double leads 24 45 and 25, which at one of their ends are connected to one of the main leads 26 of a 110-volt supply circuit.

These two leads 24 and 25 are continued in zigzag fashion and in series between the several 50 shelves and through the ducts beneath said shelves, as indicated in Fig. 6, where the dotted lines 14 represent the several shelves and the dotted line B represents the bottom of the cabinet.

5 The lead 24 constitutes a "medium" heating element, while the lead 25 constitutes a "low" heating element, and the terminal ends of these heating elements are connected respectively to one of the sides of the "low" and "medium" 10 switches 23 and 22. The other sides of these switches are connected to the other side of the 15 110-volt supply, indicated at 27.

Thus, if only switch 23 be closed, only a low 10 degree of heat will be supplied to the under sides of the several shelves. If only switch 22 be closed, then a medium degree of heat will be applied to the under sides of the several shelves, while if both of the switches be closed, then the 15 combined effect will produce a correspondingly high degree of heat upon the under sides of the shelves.

20 In the form of the invention illustrated in Fig. 7, the cabinet is substantially like that already described, except that a fan casing 28 is mounted upon the wall of the cabinet and carries an electric fan 29, driven in a common way by an electric motor 30. The fan casing carries vanes 31, in a manner common in small 25 automobile heaters and the like.

With the heat turned off in the cabinet, the fan may be used merely to circulate room temperature air in the way common to the usual electric fan, while if the heat be turned on in the 30 cabinet, then the fan may be utilized to circulate warm air to aid in warming a bathroom or other place in which the cabinet may be located.

This cabinet, which I term the Desertaire because it provides an ample supply of hot, dry 35 air, provides an economical and efficient means for heating fabrics such as clothing, towels, garments and the like. The fabrics come in direct contact with the shelf, which is directly heated by the heating element. The fabrics are also exposed to the heat from the upper portion of their 40 several compartments, i. e., from the overlying shelf containing another electrical element. This provides heat at the top and bottom of the fabrics simultaneously.

45 Fabrics consisting of towels, garments, etc., have a tendency to highly resist heat. Therefore, in order to completely and efficiently heat a large stack of cloth, heat temperatures sufficient to entirely penetrate the fabrics would probably result in the burning or scorching of the fabrics 50 closest to the heating element.

55 My multi-shelf arrangement permits the use of smaller stacks and the use of lower temperatures for thoroughly heating fabrics. When the heating element is turned on, it has a tendency to take in new air through the bottom vents and discharge air through the top vents. By using an inner cabinet comprising shelves forming compartments, and by the use of an outer cabinet 60 surrounding the inner cabinet, I create a chamber which permits installing and completely enclosing the electrical heating elements and thus provides safety for the users.

65 This chamber further provides additional efficiency for the retaining of the heat in the inner cabinet. The multi-shelf assembly provides economy in the operation of the unit by permitting the use of low wattage heating elements, threaded from one shelf to the other throughout

the cabinet. The direct contact of the low wattage element with each metal shelf has a tendency to heat the shelf to approximately the same temperature as the heating element itself; thus the fabrics which are in direct contact with the shelf consume the major portion of the heat with less loss caused by penetration.

70 The use of low wattage heating element also insures longer life of the heating element, thus providing additional economy. In one model of my Desertaire multi-shelf construction, the low heating element operates at approximately 20 watts, the medium heating element operates at approximately 35 watts, and by combining the two for our high temperature, the total is 55 15 watts. With a "high" element of 55 watts, the temperatures in this cabinet will exceed 200° Fahrenheit. Thus, it is consuming less wattage and costing less to operate than one average 20 electric lamp used in the home.

25 It will be apparent that many ways will readily suggest themselves to the skilled engineer, for bringing about changes in construction without departing from the principles involved. Therefore, it is to be understood that the invention includes within its purview whatever changes fairly come within either the terms or the spirit of the appended claims.

30 Having described my invention, what I claim is:

35 1. In combination, a hollow-walled cabinet, shelves laterally spanning the same, and spaced at their longer edges from the walls of said cabinets, ducts extending longitudinally of the shelves upon the under sides thereof, heating elements arranged in series and threaded through said ducts, the conductors of said heating elements passing between inner and outer walls of the cabinet in their passage between the shelves and door like means through which articles to be 40 dried may be introduced into the spaces between and placed upon said shelves.

45 2. A device for drying towels and like small fabric articles comprising a cabinet consisting of top, bottom, back and double end walls, substantially the entire front of the cabinet being closed by a door, a plurality of horizontally disposed shelves spaced one above the other and supported from the end walls of the cabinet, the rear edges of said shelves being spaced from the 50 rear wall of said cabinet and the front edges of said shelves being spaced from the door when the door is closed, to thereby permit the circulation of air from top to bottom of the cabinet past both sides of said shelves, conduits extending 55 longitudinally along the under sides of said shelves of a nature to permit heat to be radiated downwardly upon the tops of articles supported upon the shelf next below, electric heating elements extending longitudinally through said conduits and connected in series at the ends of said shelves, means for introducing atmospheric air below the lowermost shelf and means for conducting air from the cabinet from a point above the uppermost shelf the connections between the 60 heating elements of the several shelves being carried through the space between the said double end walls at the ends of said shelves.

65 WALTER LAWRENCE GILL.
